UNITED STATES PATENT OFFICE.

ELMER F. DWYER, OF LYNN, MASSACHUSETTS, ASSIGNOR, BY MESNE ASSIGNMENTS,
TO GENERAL ELECTRIC COMPANY, A CORPORATION OF NEW YORK.

PERFORATING AND TUBULATING MACHINE.

1,101,168.

Specification of Letters Patent. Patented June 23, 1914.

Application filed March 19, 1909, Serial No. 484,598. Renewed July 13, 1912. Serial No. 709,280.

To all whom it may concern:

Be it known that I, ELMER F. DWYER, a citizen of the United States, residing at Lynn, in the county of Essex and State of Massachusetts, have invented a new and useful Perforating and Tubulating Machine, of which the following is a specification.

After the glass bulb has been blown, in manufacturing electric incandescent lamps, 10 a hole is made in the large end, or tip of the bulb and a glass tube of small diameter is fused to the rim of the hole. Through this hole and tube, the air is withdrawn from the bulb after the filament has been placed 15 in the lamp and the stem sealed. When a vacuum has been formed in the lamp in this way, the hole is closed by heating the tube where it is joined to the bulb and drawing it to a point. The operation of making the 20 hole is called perforating, the operation of affixing the tube is commonly called tubulating, and the tube is called the tubuler. There are machines which are used in making the hole. There are also machines for affixing 25 the tubulers, and it is sometimes affixed by hand.

My invention permits the operations of 30 perforating a lamp bulb and affixing a tubule thereto to be carried on without interruption, lessens the chance of breakage by not giving the glass time to cool, increases the output, and allows the work to be done with a less degree of skill on the part of the operator than is required in the mode of 35 carrying it out above described.

The invention involves a machine for perforating the bulb and affixing a tubule thereto without removal of the bulb from the machine, and also embraces various mechanisms and combinations and arrangements of parts for dealing with lamp bulbs which are in themselves new. These combinations of parts and mechanisms and the many new features which my invention embodies will 45 hereinafter be fully described and explained with special reference to their employment in perforating and tubulating, and will be clearly indicated in my claims.

It is to be understood that I make no 50 claim broadly for the method of perforating a bulb by placing it in a holder connected with an air system and producing in it a condition of pressure different from that of the surrounding atmosphere, as this is not 55 in itself the object of my present invention.

In any machine, there is a rotary structure or table on which may be placed any convenient number of bulb holders or supports adapted to receive and hold the bulbs properly during the operations involved in affixing the tubulures. I have found that three is a convenient number, although more or fewer bulb holders may be used. There is also a hollow upright post which carries a blowpipe frame or yoke to which are affixed 60 several blowpipe fires, so adjusted that they can be concentrated on a single point. Gas and air for these fires pass through channels, ports and valves in the blowpipe frame, the supply being controlled by a foot treadle. 70 Additional means for operating upon the lamp bulbs are also arranged above the table, such means being partly carried from said hollow post and partly supported in other ways, and in the present instance comprising another fire for locally heating the wall of the lamp bulb for the purpose of perforating it and also means for affixing tubulures to the bulb with the aid of the fires first mentioned. Air is admitted to the bulb- 75 holders and bulbs through channels and ports in the table. The bulbholders on the table are so arranged that when the table is turned the bulbs pass from the flame at which the bulb is perforated to the set of 80 flames at which the tubule is attached. By operating a lever, the tubule is contracted to a very small diameter by stretching, and the tubule affixing means or clutch which holds the tubule is released 85 when the tubule has been contracted sufficiently.

It is obvious that my invention may be used with one or more bulbholders attached to the rotary table. I prefer to use several 90 of these holders, because, by doing so, while the tubule is being affixed to one bulb, another bulb is being perforated, as will be described hereinafter. Another advantage in using several bulb holders is, that it 95 enables the operator to do an increased volume of work.

In the accompanying drawings, which illustrate my invention, Figure 1 is a front view, showing the machine with a bulb in 100 each holder. Fig. 2 is a top view of the blowpipe frame, with the right half showing channels and ports, the upper part of the frame being removed for this purpose. Fig. 3 is a back elevation of the frame, the 105

right half being sectioned to show the channels and ports. Fig. 3's view also shows part of the upright hollow post. Fig. 4 is a detached top view of the clutch which holds the tubulure. Fig. 5 is a vertical section of the valve which admits the supply of gas and air, the valve being represented as closed. Fig. 6 is a detached top view of the rotary table and the base of the machine.

10 The rotary table B rests on a specially constructed base C, C having a pivot at its center around which B rotates.

C' is a bearing through which the rod P passes.

15 T is the table on which the whole machine rests.

T' is a socket which holds the supporting rod T''.

D D are upwardly opening bulb holders 20 on the table B and E E' are bulbs set in the bulb holders with their necks inclosed in them and their ends that are to be operated upon uppermost. Each of these bulb holders consists of an inner core portion d 25 which is part of B and a movable metal sleeve D set over d and made to lock by the pin d''' and slot d'', which latter serve as means for adjusting the length of the holder and hence the relative vertical positions of 30 the holder and t. Various means for operating upon the bulbs hereinbefore referred to. A strip of felt a is placed between the inner and outer parts to make them air-tight and prevent leakage. A bushing D', made 35 of rubber or other soft material, is set in the top of the holder. This construction of the bulb holder makes it possible to use any sized bulb, for, by adjusting the sleeve D the bulb can be brought into proper relation to the fires, etc.

b are channels in the rotary structure B, and b' b' are ports in B through which air is admitted to the bulb holders.

c' is a pipe through which the air passes 45 to b b' and E. This pipe c' is connected with the pipe 2 by a tube which is not shown in the drawings.

c is a pipe through which air passes through b' to bulb E'.

50 R is an upright hollow post resting on C.

R' is a collar which carries the vertically movable clutch R''. The jaws of the clutch R'' by means of which the tubulure is held and applied to the bulb move on the pivots r''' and are held together by the springs r'', so that they normally tend to close. R' is not fastened to R but is fastened to the core r' by the key r'' which moves in the slot r''' at the back of R. The collar N is fastened to 60 the hollow post R and carries a rod N' with its wedge-shaped lower end in the path of the jaws of the clutch R''.

L is a lever to which the core r' is joined by the link r.

65 L' is the fulcrum of the lever L.

A A' A'' A''' is a blow-pipe frame which is supported by the post R. This frame contains the channels a a' a'' a''' a'''' g g' g'' g''' g'''' and carries the blowpipe fires a' k, which hang downward from the frame. The valves s control the supply of gas and air passing to the fires.

H is a valve which controls the pressure of gas and air. This valve is operated by a foot treadle which is not shown but which I will call W, to which it is joined by the arm h', the chain V'', the lever V pivoted at the upper end of the rigid rod T'', and the chain V.

V''' is a spring, one end of which is fastened to the arm h'' of the valve H and the other end to the post R.

g is a slot in the valve H to allow the passage of air when the valve H is closed, as will be described more fully hereinafter.

1 is a pipe through which air is admitted to the blowpipe frame from the source of supply.

3 is a pipe through which gas is admitted to the blowpipe frame from the source of supply.

P is a movable rod and is connected with a treadle not shown but which I will call U, herein.

y is a supporting rod for the movable rod P.

M is a relatively stationary clutch which engages the projection m on the structure B when the treadle U is operated to depress it against the action of the spring S, thus serving as a means for holding the rotary structure B temporarily arrested.

a, k, is a blow-pipe burner carried on the rod P.

F is a bracket mounted on the rod P which moves downwardly and engages or fits over the upper end of the bulb when the treadle U is operated, this bracket F being thus controlled and actuated in unison with the blow-pipe burner a, k.

K is a pipe through which gas passes to the burner k.

K' is a pipe through which air passes from the source of supply through the connections p' p'' to the blowpipe a, the flame being thus directed downward.

p''' is a bracket which steadies the blow-pipe burner parts a, k carried on the rod P.

The machine is operated in the following manner: After the bulbs have been placed in the bulbholders, the table is turned by hand until one of the bulbs is directly under the burner k. The foot treadle w is then operated, which causes the table arrester clutch M to engage one of the projections m and thus lock the table B so that it cannot rotate and simultaneously forces the relatively stationary bulb steadiers bracket F down upon the bulb E', and in this way the bulb is centered and steadied in a defi-

nite position with reference to the bulb holding means D, and other parts. The relatively stationary burner k, and blow-pipe a^v carried by the movable support P are also lowered by the same operation to a position convenient for heating the bulb. When the downwardly directed flame from k, a^v has heated the top of the bulb sufficiently, the bulb is perforated by a current 5 of air which passes from the source of supply through the passages and connections c b b' above described and the holding means D to the bulb, the flow of air being controlled by a pinch cock on the pipe leading 10 to the source of supply, or by other suitable means. When the bulb has been perforated the foot treadle U is released and the spring S forces the rod P upward, carrying the clutch member m, the bracket F, and the 15 blow-pipe burner k, a^v up far enough to release the projection m and the bulb, and to allow free rotation of the table. While the bulb is being perforated at E', a tubulure is placed or inserted sidewise in the clutch 20 R''. After the bulb has been perforated, the table is turned, bringing the bulb with the perforation in it to the front of the machine at E, the hole in the bulb coming directly under the tubulure e. The bulb at 25 E' is then in position for being perforated, and that operation proceeds as already described. At the same time, the operator presses down the lever L until the end of the tubulure is close to the hole in the bulb. 30 By operating the treadle W, air is forced through the pipe 1, the holes in the valve II between 1 and a (Fig. 5), through the channels a a, a' a'' a''' and a^v to the blow pipes a^v and at the same time gas is forced 35 through the pipe 3, the hole in II between 3 and g (Fig. 5), the channels g g, g' g'' g''' and g^v to the burners k by means of which the tubulure and the walls of the bulb are heated. In my machine, I use a set of four 40 fires a^v k, all of which hang downward and are so adjusted as to concentrate their flames upon the perforation in the bulb and the end of the tubulure e, but more or fewer fires may be used. When the glass has been 45 heated to the fusing point, the lever L and the relatively stationary tubulure affixing means R'' are lowered until the tubulure comes in contact with the rim of the perforation. Then the flames are diminished by releasing the treadle W, which allows the 50 spring V''' to close the valve II. The operator then raises the lever L. This contracts the tubulure to a very small diameter at the point where it is joined to the bulb. As 55 the lever L is raised, carrying up the clutch R'' and contracting the tubulure e, the jaws of the clutch R'' are forced open by means of the wedge-shaped lower end of the rod N', thus preventing the tubulure e from being contracted too much. When the tu-

bulure e is released by the wedge N', the bulb and tubulure are removed and another bulb placed in the holder. By this time, a hole has been blown in the next bulb, which is then brought to the front by turning the 70 table and the work continued as described. By means of a tube connecting the pipe 2 with the pipe e', a current of air is injected into the bulb. The air is admitted to the bulb and the inside of the tubulure while the tubulure is being contracted to the proper degree and cools off the tubulure at the contraction, thus stiffening it so that when it is released from the clutch it will stand alone. The air passes from 1 through 75 the channel g in the part II to 2 and thence to e', as described. 80

By the use of my machine, the operator is kept busy constantly and the machine, by simple operations, is made to bring fresh 85 bulbs and tubulures within the range of the fires.

What I claim as new and desire to secure by Letters Patent of the United States is:—

1. A machine for operating upon lamp bulbs comprising a rotary structure having upwardly opening bulb holding means adapted to receive and inclose the necks of a plurality of bulbs and to support them with their ends to be operated upon uppermost, there 90 being means for producing in the bulbs conditions of pressure different from that of the atmosphere, heating means arranged to direct a single perforating flame downward on the wall of the bulb when the bulb is by rotation of said structure brought into position to be operated on by said heating means, means for affixing a tubulure to the bulb comprising means for holding the tubulure movable downward to apply 95 it to the bulb, and means for heating the tubulure and the wall of the bulb where it is to be applied, said perforating heating means and said tubulure affixing means being so arranged relative to said rotary 100 structure and to one another that when one bulb is in position to be operated on by the former another bulb will be in position to be operated on by the latter.

2. A machine for operating upon lamp bulbs comprising a rotary structure having upwardly opening holding means adapted to receive and inclose the necks of a plurality of bulbs, there being passages and connections from the holding means for producing in the bulbs conditions of pressure different from that of the atmosphere, relatively stationary means for locally heating the wall of a bulb and for affixing a tubulure thereto arranged so that by rotation 115 of said structure the bulbs may successively be brought beneath the same and that when one bulb is beneath the former another will be beneath the latter, and means for temporarily holding the rotary structure ar- 120 125 130

rested in a definite position and for centering the upper end of a bulb with reference to the arresting holding means so as to insure that the bulb shall be properly operated upon by both heating and tubulating means, said centering means being movable downward and upward to engage the bulb and release it.

3. In a tubulating machine, the combination of a rotary table carrying a plurality of bulb holders, with ports and channels and means for allowing air to enter the bulbs, a movable support carrying a blow-pipe flame, means for holding the bulbs in proper position relative to the blow-pipe flame, a movable clutch to hold the tubulure and means for operating and opening the clutch, means for heating the bulb and tubulure, means for affixing the tubulure to the bulb and for contracting the tubulure, and means for locking and releasing the table.

4. A tubulating machine having an upright hollow support carrying a yoke or blow-pipe frame with valves, channels, and blow-pipe burners, a rotary table with bulb holders, a movable support with a blow-pipe burner, a bulb steadier, and a table arrester, a movable clutch to carry the tubulure, means for perforating the bulb at the preliminary flame from the blow-pipe associated with said movable support, means for operating the clutch carrying the tubulure, means for affixing the tubulure and for contracting the tubulure, means for releasing the tubulure, and means for cooling the tubulure while it is being contracted.

5. A bulbholder with a hollow core within a movable sleeve, a bushing surmounting the core and sleeve, means for preventing leakage between the core and sleeve, and means for regulating the length of the bulbholder.

6. The combination with relatively stationary means for operating upon a lamp bulb and a rotary structure comprising holding means adapted to receive the lower end of a bulb and support the bulb with its end to be operated upon uppermost, said structure being adapted by its rotation to bring the bulb in the holding means into position to be operated upon by said operating means, of means for temporarily holding the rotary structure arrested in a definite position and relatively stationary means for bringing the upper end of the bulb to a definite position with reference to the holding means while the structure is so held arrested.

7. The combination of holding means adapted to receive the lower end of a lamp bulb and to support the bulb with its end to be operated upon uppermost, movable means for operating upon the lamp bulb adapted to be brought downward to operate upon it, and means for engaging the upper

end of the bulb to bring it to a definite position with reference to said operating means and steady it controlled and actuated in unison with said operating means so as to come into engagement with the bulb when said operating means approaches it and to recede and release the bulb when said operating means moves away from it.

8. The combination with relatively stationary means for operating upon a lamp bulb and a rotary structure comprising holding means adapted to receive the lower ends of a plurality of bulbs and to support the bulbs with their ends to be operated upon uppermost, said structure being adapted by its rotation to bring said bulbs successively beneath said operating means, of means for temporarily holding said structure arrested with any of said bulbs beneath said operating means, and relatively stationary means by whose movement said means for holding the rotary structure arrested is controlled adapted to move downward into engagement with the bulb beneath said operating means to bring the bulb to a definite position with reference to said operating means and steady it and to move upward out of engagement with the bulb so as to allow the rotary structure and the bulb to be revolved.

9. The combination of means for holding a lamp bulb and for heating a tubulure, tubulure holding means movable toward and away from the bulb to affix a heated tubulure thereto and to contract the same, and means for causing said tubulure holding means to open and release the tubulure when the same has been sufficiently contracted by movement of said tubulure holding means away from the bulb.

10. The combination of means for holding a lamp bulb, means for affixing a tubulure thereto comprising tubulure holding means normally tending to close into which a tubulure may be inserted sidewise and from which it may in like manner be removed, said tubulure holding means being movable toward and away from the lamp bulb, and means whereby the tubulure holding means is caused to open when moved away from the bulb a certain distance, so that when a tubulure has been applied to the bulb by movement of said holding means toward the bulb and contracted to the desired extent by movement of said holding means away from the bulb said holding means shall open so as to prevent further contraction of the tubulure and permit the bulb with the tubulure attached to be removed from the holding means.

11. The combination of means for holding a lamp bulb, means for affixing a tubulure thereto comprising tubulure holding means movable toward and away from the bulb, consisting of jaws which automatically

cally tend to close and into which a tubulure may be inserted sidewise and from which it may in like manner be removed, and wedge-shaped means arranged in the path of movement of the jaws so that when the tubulure has been applied to the lamp bulb and contracted to the desired extent

by movement of the tubulure holding means away from the bulb said wedge means will come between the jaws and force them open. 16
